UNITED STATES PATENT OFFICE

144,779

DESIGN FOR A CABINET PRESSING MACHINE

Wallace F. Gayring, Minoa, N. Y., assignor to
The Prosperity Company, Inc., Syracuse, N. Y.,
a corporation of New York

Application June 5, 1945, Serial No. 119,907

Term of patent 14 years

(Cl. D49—1)

To all whom it may concern:

Be it known that I, Wallace F. Gayring, a citizen of the United States, residing at Minoa, in the county of Onondaga and State of New York, have invented a new, original, and ornamental Design for a Cabinet Pressing Machine, of which the following is a specification, reference being had to the accompanying drawing, forming part thereof.

In the drawing:

The figure is a perspective view of a cabinet

pressing machine embodying my new design. The other end of the machine, not shown, is substantially like the end shown. The lower pressing element is shown in broken lines.

The dominant features of the design reside in the portions shown in full lines.

I claim:

The ornamental design for a cabinet pressing machine, substantially as shown and described.

WALLACE F. GAYRING.
